UNITED STATES PATENT OFFICE

MICHAEL J. GRAHAM AND ARTHUR HOLSEY, OF CHICAGO, ILLINOIS, ASSIGNEES TO
INTERNATIONAL HARVESTER COMPANY, A CORPORATION OF NEW JERSEY

CIRCUIT BREAKER

Application filed February 18, 1929. Serial No. 340,717.

This invention relates to circuit breakers. Ignition systems deriving energy from magneto generators or the like usually employ a circuit breaker structure to induce a hot spark for ignition purposes in engines, for example. These circuit breakers are quite conventional and embody a cam ring, manually adjustable within a sleeve, and frictionally held in contact therewith, to regulate the time of sparking by advancing or retarding the cam ring relative to the breaker.

Eventually, it has been found, the repeated turning of the cam ring causes wear so that it no longer frictionally engages in the sleeve to maintain the desired advanced or retarded position.

Accordingly, it is the primary object of this invention to improve the structure and operation of circuit breakers of the kind used in connection with magneto or other current generators.

Another object is to provide structure for the adjustable cam ring that will automatically compensate for any wear thereon, or on the sleeve which carries the ring, so that the ring and sleeve will at all times be in proper frictional engagement.

Other objects will be apparent as the disclosure continues.

These desirable objects in the illustrative embodiment of the invention to be disclosed are accomplished in the provision of an elongated depression in the outer surface of the cam ring, said depression receiving, loosely, a stiff flat spring element, arcuated to a more pronounced curvature than the curve of the cam ring. Thus, with the spring in the depression, the cam ring will have to be forced into the bearing sleeve, the pressure causing the spring element initially to flatten slightly so that it is caused to assume a curve substantially coincident with the outer curved surface of the ring. The ring is now in operative position and capable of turning movement in the bearing sleeve. As wear takes place between the ring and bearing sleeve surfaces, the spring element automatically compensates for such wear because it moves out radially from its depression to engage yielding against the sleeve. This action main-

tains the two cooperative parts in frictional engagement at all times, as can now be readily understood.

In the accompanying sheet of drawings showing an illustrative embodiment of the invention,

Figure 1 is a face view of a part of the circuit breaker assembly as applied to a magneto generator, the view being along the section line 1—1 seen in Figure 2, when looking in the direction of the arrows;

Figure 2 is a vertical cross sectional view of the same structure as viewed along the line 2—2 of Figure 1, looking in the direction of the arrows;

Figure 3 is a detached, inner face view of the cap and adjusting arm part;

Figure 4 is a perspective view of the cam ring per se; and,

Figure 5 is a detailed, cross sectional view, on an enlarged scale, to illustrate the compensating spring in place in the cam ring depression.

In these drawings a magneto generator has been generally illustrated at 10. A mounting plate 11 including a carrier sleeve 12 is secured by bolts 13 to the magneto. The carrier sleeve 12 has arranged therein the usual bearing sleeve 14 which includes a flange 15 carrying a stop set screw 16 for a purpose later to appear.

Arranged in the bearing sleeve 14 for frictional turning movement therein is the usual cam ring 17 having the usual inner, diametrically opposed cam surfaces 18. An adjuster cap 19 having an operating control arm 20 formed therewith is turnably mounted by means of the flange 21 on the carrier sleeve 12.

The cap also includes an inner flange 22 having tongues 23 for engagement in complementary cut outs 24 so that when the cap, by means of the arm 20, is advanced or retarded, the same turning movement will be communicated to the cam ring which regulates the circuit breaker. The circuit breaker has not been illustrated, as this is well known in the art. A cut out 25 in the cam ring cooperates with the set screw 16 to limit the angular distance through which the cam ring may be adjusted.

After a time, the repeated adjustment of the cam ring in the bearing sleeve causes the touching surfaces to wear, which destroys the frictional contact, making a loose cam ring fit and preventing the cam ring from being effectively maintained in any desired adjusted position. In the past, this wear necessitated replacement of the cam ring.

The present invention provides an automatically acting wear compensator structure which materially prolongs the life of the cam ring and overcomes the difficulties heretofore encountered due to such objectionable wear.

Accordingly, in the illustrative form of the invention a depression or groove 26 is formed preferably on the outer wear surface of the cam ring, the depression having end walls 27. Arranged in this depression is a flat, stiff spring element 28 performed to a curvature somewhat more pronounced than the curvature of the outer surface of the cam ring. The spring element is of a length to cause its ends normally to stop short of the end walls 25 of the depression. See Figure 5.

It can now be seen that, when the cam ring is frictionally fitted into the bearing sleeve, the spring element 28 will be flattened or distorted from its performed shape. The ends 30 of the spring element 28 are thus caused to abut the end walls 27 of the depression 26.

The parts are thus assembled for use. When the cap member 19 is turned, the cam ring is also turned to vary the time of operation of the circuit breaker to advance or retard the sparking action in the well known manner. These repeated adjustments of the cam ring cause wear of the outer surface of the ring and also of the adjoining bearing sleeve surface. Such wear obviously destroys the frictional contact between these parts and is highly objectionable because friction alone is relied upon to hold the cam ring in adjusted position. With the provision 45 of the spring of this invention any such wear will be automatically taken up, or compensated for, because the spring element 28, when wear takes place, presses radially out because of its inherent tendency to restore itself to 50 the initial preformed shape. The incident spring pressure, therefore, causes the parts described to be retained in frictional contact, which is so desirable and necessary. In practice the cam ring is made of steel, and 55 the bearing sleeve of brass and aluminum. Heat and cold effect expansion and contraction of these parts differently. Thus, the structure of this invention will also compensate automatically for these changes and cause 60 the cam ring properly to fit in the bearing sleeve.

It must now be appreciated that this invention accomplishes all of the desirable objects heretofore recited.

65 Obvious changes may be resorted to by

those skilled in this art without departing from the invention as is indicated by the scope of the appended claims.

What is claimed is:

1. In a circuit breaker, a bearing sleeve, a cam ring frictionally retained therein and adapted for angular adjustment relative thereto, a groove in the ring having end stop walls, and a preformed flat spring arranged in the groove with its ends initially contacting the stop walls when distorted from its initial preformed shape, said spring exerting pressure and tending to resume its initial preformed shape as wear takes place between the sleeve and ring to compensate for such wear and retain said parts in frictional engagement. 70

2. In a circuit breaker, an annular bearing sleeve, an annular cam ring frictionally retained therein and adapted for angular adjustment relative thereto, a relatively short groove provided in the outer surface of the ring, said groove having end walls, a short flat spring arranged loosely in the groove and preformed to the curve of an arc less than the curvature of the ring, said spring adapted to be distorted by pressure to conform to the curve of the ring with its ends abutting the end walls of the groove, whereby the ring with the spring may be frictionally fitted into the sleeve, said spring gradually resuming its initial preformed curvature as wear takes place between the sleeve and ring. 80

85 In testimony whereof we affix our signatures.

ARTHUR HOLSEY.
